HAND OPERATED HAIR CLIPPER

Application filed July 29, 1929. Serial No. 381,989.

This invention relates to a hand operated clipper especially designed and adapted for removing the hair under the arm pits.

For various reasons, it is desirable to use hair clippers for the purpose of removing hair from under the arm pits, but it has been found that the present types of hair clippers are ill adapted for this purpose principally because the known clippers are so constructed 10 and so operated as to be incapable of following the contour of the flesh in the region of the arm pits and also because all prior types of clippers are designed for use with one hand only. Concerning the latter feature of the 15 prior types of hand clippers it is to be noted that such clippers have a stationary handle and a movable handle. This arrangement makes it possible to operate the clippers with one hand only and if such a clipper is shifted 20 to the other hand it will be found practically impossible to effectively use the clipper for the reason that the clipper may not be held steady while operated.

Among the important objects of the present 25 invention are to provide a hand operated clipper which is adapted for convenient and effective operation with either hand and which is so constructed and organized that it readily and easily follows the contour of the 30 flesh in the region of the arm pits and does so in such a manner as to effect very close clipping of the hair without any pulling and without any abrading or irritating action on the flesh.

In carrying out the present invention a hair 35 clipper is provided which consists broadly of coacting blades mounted on one end of a handle member in such manner that when the clipper is in use it operates with a hoe or razor-like action, that is to say, the clipper when exerting a cutting action is advanced with a backward or pulling stroke instead of with a forward or pushed stroke as 40 in the conventional clippers. This feature is one of the principal factors in the ability of the clipper to follow the contour of the flesh in the region of the arm pits and to effectively remove or clip hair in such regions. In 45 addition the operating mechanism provided for the clipper blades, the manner of its or-

ganization with the handle and with the blade, is such as to provide for easy and convenient operation of the clipper with either hand.

Other objects and advantages reside in certain novel features of the construction, arrangement and combination of parts which will be hereinafter more fully described and particularly pointed out in the appended claims, reference being had to the accompanying drawing forming a part of this specification, and in which:

Figure 1 is a view in front elevation showing a hand operated clipper embodying the present invention;

Figure 2 is a view in section on line 2—2 of Figure 1, parts being shown in elevation for the sake of simplicity and illustration;

Figure 3 is a top plan view of the clipper, parts being broken away and parts being shown in section for the sake of illustration; and

Figure 4 is a view in horizontal section taken on line 4—4 of Figure 2.

Referring to the drawing, numeral 1 designates generally a handle which includes an outer part or casing 2 shaped to be conveniently gripped in the hand and having a socket 3' in which a shank 4 is frictionally fitted and releasably secured by means of a lock screw 5. The shank 4 projects above the upper end of the casing or covering 2 and has a reduced extension or post 6 formed integral therewith.

On this post 6 a fixed blade 7 and a coacting movable blade 8 are mounted. The fixed blade 7 has an internally threaded opening 7' therein and with this internally threaded opening 7' the threaded outer end 5' of the post 6 is threadedly engaged. In order to lock the fixed blade 7 in position on the post 6 and also to secure tensioning means in place, a nut 9 is engaged with the threaded portion 5' of the post 6 inwardly of the fixed blade 7 and this nut 9 has binding or clamping engagement with one end of a spring tension member 10, this spring tension member 10 being apertured and fitted over the post 6 and being interposed between the nut 9 and the fixed blade 7. The movable blade 8 is

shown as to its outline in Figure 4 and as shown in Figure 2 the spring tension member has its outer portion downwardly offset so that it extends beneath the blade 8, but its extremity is upwardly deflected as at 10' to bear against the movable blade 8 and urge it with the proper tension against the fixed blade 7 and yet develop a minimum of friction between the movable blade 8 and the 10 spring tension member 10.

A sleeve 12 is fitted on the inner smooth portion of the post 6 for oscillating movement and the inner end of the sleeve 12 has integral therewith or otherwise suitably fixed thereto 15 a knurled collar 13 which is utilized by the operator for oscillating the sleeve 12. The outer end of the sleeve 12 has flat faces 12' formed thereon so that this outer extremity of the sleeve is of non-circular cross section and 20 is adapted to snugly fit into a correspondingly formed opening 14' provided in the body portion 14 of a carrier or driving member designated generally at 15. The carrier or driving member 15 includes not only the body portion 14, but also upwardly offset arms 16 which are riveted as at 16' to the movable blade 8.

The operating parts are enclosed in a housing made up of a lower section 20 which has 30 a body portion apertured as at 21 (see Figure 4) to permit free movement of the sleeve 12 relative thereto. This lower section also has the forward end of its body portion upturned as at 22 to engage the under surface of the 35 blade 8 without restraining movement of the blade. At its sides the lower section has upturned flanges 23 which abut the fixed blade 7 along its under surface and adjacent its side edges, but which are sufficiently spaced to permit 40 the movable blade to have the requisite freedom of movement. Along its rear edge, the housing 20 has an upturned flange 24 which overlaps the rear edge of the fixed blade 7 and which is provided with openings 45 24' registering with the threaded openings 25 in the rear of the fixed blade 7 when the lower housing section is properly assembled. The housing is completed by an upper housing section designated generally at 28 and 50 having a slightly curved body portion, the forward edge which merges into the top surface of the blade 7. This body portion 28 may be longitudinally corrugated if desired. The 55 side edges and rear edge of the body portion 28 are provided with flanges 29 for the side edges and 30 for the rear edge, the flanges 29 snugly overlapping the side edges of the fixed blade and the flange 30 snugly overlapping 60 the upturned flange 24 of the lower housing section. This flange 30 also has openings 30' registering with the openings 24' and 25 in the assembly and permitting of the insertion of screws 31 which engage with 65 the threaded openings 25 and coact with the

flanges of the rear of the housing sections to releasably secure the housing in position.

In assembling the clipper the shank 4 is first introduced into the handle casing 2 and locked in position by the screw 5. The sleeve 12 is then slipped over the post 6 and the lower section 20 of the housing is dropped over the sleeve, that is, its aperture is passed down onto the sleeve 12. The movable blade 8 with its driving member or carrier 15 is next 75 assembled, the non-circular opening 14' of the carrier or driving member 15 being assembled with the correspondingly non-circular portion 12' of the sleeve 12. This provides a connection between the movable blade 8 and the sleeve 12 which constrains the blade 8 to rotate or oscillate with the sleeve 12. Any suitable releasable fastening means may be provided for this purpose. It is desirable 80 that the fastening means be releasable to permit of easy assembly and disassembly for purposes of cleaning, lubrication, repair and replacement. After the driving member has been assembled the nut 9 is threaded on the threaded extremity 5' of the post, the tension member 10 is placed in position, the blade 7 threaded onto the outer end of the post 5 until it is properly positioned whereupon the nut 9 is tightened up to lock the blade 7 in 85 position and also to secure the tension member 10 in position. The housing section 28 is then applied and the housing section 20 is brought up into position and both housing sections are secured in place by the screws 31.

In operation the user may hold the clipper 90 in either hand and grasp the handle between the palm of the hand and the two middle fingers and the little finger. The forefinger or index finger and thumb grasp the knurled collar 13. In this way it is very easy to twist 95 or oscillate the knurled collar 13 and thus reciprocate the movable blade 8. The outer edges of the teeth of the movable blade 8 and of the fixed blade 7 lie in an arc which has the axis of the post 6 as a center so that oscillation of the sleeve 12 in the manner described 100 will cause the movable blade to effectively coact with the fixed blade to clip and remove hair. Due to the relation or organization of the blades with the post, or in other words, 105 the fact that the blades are arranged transversely at the outer end of the post or in a plane at right angles thereto, it is convenient and in fact necessary to advance the clipper 110 during cutting with a downward or pulling stroke somewhat after the manner of a safety razor instead of with a pushing stroke as in ordinary clippers. This permits the clipper 115 to follow the contour of the flesh in the region of the arm pits and to effectively remove hair thereon. It is obvious that the clipper may 120 be used with equal effectiveness in either hand inasmuch as the relation to the operating means, that is, the collar 13 and sleeve 12, does not change in any material way with respect 125 130

to the hands when the clipper is shifted from one hand to the other.

Along with these advantages the clipper is simple and of durable construction, its parts 5 are easily accessible for cleaning and lubrication, replacement and repair and it lends itself to economical manufacture by facilities and from materials ordinarily obtainable. While a clipper embodying the present invention 10 is especially designed and adapted for removing hair under the arm pit, in general this clipper may be used to advantage in places where a regular standard type of hand clipper may not be effectively or satisfactorily 15 employed.

The invention claimed is:

1. A hand operated hair clipper comprising a handle having a main portion, coacting blades mounted on one end of the handle and 20 arranged transversely and at right angles thereto whereby the blades are adapted to be advanced during cutting with a downward pulling motion and operating means for the blades including an oscillatory sleeve intermediate the blades and the main portion of 25 the handle, means connecting said sleeve to one of the blades and means on said sleeve adapted to be grasped between the thumb and forefinger of the same hand that grasps the 30 handle.

2. A hand operated clipper comprising a handle, a fixed blade extending transversely to the handle and secured thereto adjacent one end thereof, a movable blade coacting 35 with the fixed blade, a tension member mounted on the handle, means for forcing the tension member against the fixed blade and for biasing it to bear against the movable blade to cause the movable blade to engage 40 the fixed blade with the proper tension and means mounted on the handle for operating the movable blade.

3. A hand operated clipper comprising a handle, a separate fixed blade extending 45 transversely of the handle and secured thereto near one end thereof, a separate movable blade coacting with the fixed blade, a sleeve mounted for oscillation on the handle and a driving member secured to the movable blade 50 and interconnected with the sleeve so as to be oscillated thereby.

4. A hand operated clipper comprising a handle, a fixed blade secured to the handle near one end, a movable blade coacting with 55 the fixed blade, a tensioning member for urging the blades to engage each other with the proper pressure, a sectional housing secured to the fixed blade and enclosing the fixed and movable blades and the tension member and 60 operating mechanism for the movable blade including a sleeve mounted on the handle outside of the housing and having a portion projecting therein and a driving connection between said portion and the movable blade.

65 5. A hand operated clipper comprising a

handle having a post extending axially from one end thereof, a blade fixed to one end of the post and extending transversely thereto, a sleeve rotatable on the post, a driving member connected to the sleeve, a movable blade 70 secured to the driving member and coacting with the fixed blade, and a spring tension member fixed to the post and bearing up against the movable blade to urge it to engage the fixed blade with the proper pressure. 75

6. A hand operated clipper comprising a handle having a post extending from one end thereof, a blade threadedly connected to the outer end of the post and extending transversely thereto, a sleeve rotatably fitted on the post, a driving member connected to the sleeve, a movable blade secured to the driving member and coacting with the fixed blade, a spring tension member having one end 80 mounted on the post and one end cooperable with the movable blade and a nut threaded on the post to clamp the spring tension member and fixed blade in operative position. 85

7. A hand operated hair clipper comprising a handle having a post extending axially 90 therefrom, a fixed blade secured adjacent the outer end of the post, extending transversely thereto and having teeth disposed in an arc struck from the axis of the post as a center, a movable blade mounted for oscillatory 95 movement about the post as an axis and having teeth disposed in an arc struck from the post as a center and cooperable with the teeth of the fixed blade, the axes of the teeth of each blade being parallel and means for moving the movable blade back and forth in an arc which has the post as a center. 100

In witness whereof, we hereto affix our signatures.
